UNITED STATES PATENT OFFICE.

EMIL TALAMINI, OF NEW YORK, N. Y.

DESIGN FOR A TILE-FACING.

42,405.

Specification for Design.

Patented Apr. 9, 1912.

Application filed November 11, 1911. Serial No. 659,838. Term of patent 14 years.

To all whom it may concern:

Be it known that I, EMIL TALAMINI, a citizen of the United States, residing at New York, in the county and State of New York, have invented a new, original, and ornamental Design for a Tile-Facing, of which the following is a specification, reference being had to the accompanying drawing, forming a part thereof.

The figure is a plan view of a portion of a tile facing showing my new design the characteristic features of which are the oblong tile 1, having straight sides and V-shaped ends each side of which is at an angle of sixty degrees to the side of the tile, prolonged, or which forms an obtuse angle with the side of the tile of one hundred and

twenty degrees; and triangular tile 2. The tile being thus formed are placed together to form my new design in which three of the tile 1, have their apexes of one end at a point, as 3, and three of the tile 1, fit in the angles 4, formed by the first three; the other ends of the tile 1, are reversed to that above described, and the intervening spaces are filled by the triangular tile 2, as shown.

I claim:

The ornamental design for a tile facing, as shown and described.

New York, November 8, 1911.

EMIL TALAMINI.
